CLAIM

The ornamental design for a rod assembly for a sharpening device used to sharpen a cutting tool, as shown and described.

DESCRIPTION

FIG. 1 is a perspective view of the design.

FIG. 2 is a front view of the design of FIG. 1.

FIG. 3 is a rear view of the design of FIG. 1.

FIG. 4 is a top plan view of the design of FIG. 1.

FIG. 5 is a bottom plan view of the design of FIG. 1.

FIG. 6 is a right side view of the design of FIG. 1; and,

FIG. 7 is a left side view of the design of FIG. 1.

1 Claim, 4 Drawing Sheets
